UNITED STATES PATENT OFFICE

2,600,926

RADIAL LOUVER CONSTRUCTION

Gene C. Rudd, Fort Worth, Tex., assignor to
 Southern Air Conditioning Mfg. Co., a partnership comprised of Gene C. Rudd and Charles B. Rudd of Fort Worth, Tex.

Application July 1, 1949, Serial No. 102,521

1 Claim. (Cl. 98—40)

1

This invention relates to improvements in louvers for evaporative air cooling units and the like.

An object of the invention is to provide a louver assembly having radially disposed louvers which may be conveniently adjusted independently of each other so as to control the direction of air passing therethrough.

Another object of the invention is to provide a simplified construction for frictionally engaging the inner ends of the radially disposed louvers for maintaining them in their desired positions.

Another object of the invention is to provide, in combination with a portable evaporative type cooler, a louver construction and arrangement whereby air passing through said cooler may be directed laterally from any side thereof.

These and other objects of the invention will become apparent from the following description and accompanying drawing, wherein:

Figure 1 is a plan view of a portable evaporative cooler and showing the present louver construction mounted thereon.

Figure 2 is a broken side elevation of the cooler and louver combination illustrated in Figure 1.

Figure 3 is a broken enlarged vertical sectional view of the upper end of the louver illustrated in Figures 1 and 2.

Figure 4 is a broken perspective view of the construction illustrated in Figure 3.

Figure 5 is a perspective view of the louver supporting frame, and

Figure 6 is a perspective view illustrating the present invention positioned in a box type cooler or the like.

The numeral 10 generally designates a louver supporting frame including a polygonal ring 11 at the center and downwardly and outwardly disposed legs 12 projecting therefrom. The ends of the legs terminate in downwardly formed eyelets 13 for securing the frame over the opening to be louvered.

The assembly shown includes a plurality of louvers 14 which are substantially in the form of segments and have their inner ends rolled, as at 15, to hingedly engage the sides of the polygonal ring 11. Beneath the rolled inner ends 15 of the louvers 14 there is a disk 16 having a bolt 17 slidably and perpendicularly positioned through its center. The upper end or head of the bolt 18 is supported within a U-shaped bracket 19 which, in turn, is secured to the inner surface of a cap 20 positioned above and in contact with the rolled inner ends 15 of the louvers 14. The lower extending end of the bolt 17 is

5 provided with a pair of spaced washers 21 having a compression spring 22 therebetween. A nut 23, threadedly engaged on the end of the bolt 17, bears against the lowermost washer 21; and by reason of the location of the compression spring 22, the rolled ends 15 of the louvers 14 are frictionally engaged, and whereby said louvers may be manually and selectively positioned at desired angles with respect to the axial center of the louver assembly. The amount of friction applied may be controlled by adjusting the nut 23.

10 It is to be understood that the described louver assembly is capable of many applications, such as over an opening in a wall (not shown), or over an annular opening 24 in a box type evaporative cooler, generally designated by the numeral 25 in Figure 6.

15 The present louver assembly is particularly adaptable to a portable evaporative cooler 26, as shown in Figures 1 and 2. The cooler 26 includes a circular pan 27 having an upwardly and inwardly directed flange 28 around its periphery, and an annular ring 29 secured beneath the inner edge of said flange. An open mesh cylindrical housing 30 is secured to the ring 29, and extends upwardly above said pan where an upper and inwardly flanged ring 31 is secured to the upper end of said housing. Beneath and secured to the upper ring 31 there is an annular channel 32 having small openings 33 in its lower surface. A cylindrical cooling pad 34 of excelsior or the like is positioned between cylindrically formed screen wire 35 and 36, said pad and the supporting wire 35 and 36 extending downwardly into the bottom of the pan 27.

20 Inwardly of the inner screen 36, and supported on the bottom of the pan 27, there is a water pump 37 having an upwardly extending discharge tube 38 connected at its upper end with a water distributor 39, which in turn is connected with supply tubes 40 communicating with the interior of the annular channel 32. The last described arrangement of pump 37, discharge tube 38, and water distributor 39 raises water from the pan 27 and into the channel 32 from where the water trickles downwardly through and over the cooling pad 34.

25 A U-shaped bracket 41 secured to the inner surface of the channel 32 supports a motor 42 having its shaft 43 vertically and upwardly extending, and upon which a fan 44 is mounted. The rotation of the fan 44 is such that air is drawn inwardly through the open mesh housing 30 and through the cooling pad 34, thence up-

wardly and outwardly through the channel 32. By manually positioning and spacing the louvers 14 relative to the upper end of the cooler 26, the amount of air passing therethrough can be controlled; and by selectively raising certain of said louvers only, the flow of air may be controlled as to lateral direction.

Other details of the evaporative cooler 26 includes casters 45 secured beneath the lower surface of the pan 27, and screws 46 passing through the frame eyelets 13 and threadedly engaged in the channel 32.

The described form of the invention may be made in many ways within the scope of the appended claim.

What is claimed is:

In a louver assembly, the combination of: a central supporting ring, radially arranged louvers hingedly mounted at their inner ends on

said ring, a cap above and in contact with said inner ends of said louvers, a disk beneath and in contact with the under ends of said louvers, and spring means pressing said cap and said disk toward each other.
